poration of New Jersey

Application August 23, 1934, Serial No. 741,110

14 Claims.

(Cl. 12—42)

This invention relates to machines for driving linear work pieces, such as nails, tacks, dowels and the like, and the illustrated embodiment thereof is a machine of the type shown in the application of Frank T. Gentile, Serial No. 637,735, filed October 14, 1932, to which reference may be made for details not exhaustively explained herein.

The machine shown in the Gentile application 10 is intended for driving polygonal lining tubes into holes extending perpendicular to the top-lift faces of wood heels. These tubes serve to hold the shanks of replaceable top lifts. The Gentile machine comprises a hopper and a raceway for 15 feeding the tubes, and a transfer member for receiving the tubes from the raceway and moving them to driving position.

It is an object of the present invention to effect 20 certain improvements in the machine shown by Gentile, while sacrificing none of its advantages.

In accordance with a feature of the invention, we have provided an organization of raceway, transfer member and detent or detaining member, such that all the tubes in the raceway except 25 the lowest one are detained until that lowest one has been received and removed by the transfer member. Preferably, also, and in accordance with a second feature of the invention, the transfer member itself acts as a closure for the race- 30 way, and supports the lowest (undetained) tube until the transfer member has come into position to receive that tube. Thus any tube is either completely in or out of the transfer member at any time, and danger of clogging is minimized.

The illustrated machine is automatic and provided with a clutch which may be tripped to start the driving operation, and in accordance with another feature of the invention it is provided that the clutch shall not be tripped until the 40 transfer member has reached driving position, thus avoiding danger of jamming the mechanism.

Other features of the invention relate to a 45 novel agitator member and to a device for preventing clogging of the work pieces at the entrance to the raceway.

These and other features of the invention comprising certain combinations and arrangements of parts will be apparent from the following description of a preferred embodiment of the invention shown in the drawings, in which

Fig. 1 is a front elevation of the machine;
Fig. 2 is an elevation of the left side of the ma-
chine;

Fig. 3 is an enlarged detail of the hopper mechanism;

Fig. 4 is a plan view of the heel supporting table;

Fig. 5 is a bottom plan view of the clamp member; 5

Fig. 6 is a rear view of the transfer mechanism just after reception of a tube;

Fig. 7 is a rear view of the transfer mechanism just after movement to driving position; 10

Fig. 8 is a cross-section of the transfer mechanism showing the indenting tool;

Fig. 9 is a broken-away detail showing a tube and driver in position in a heel just before removal of the driver; and 15

Fig. 10 is a cross-section on the line X—X of Fig. 9.

The main frame 10 has a column 12 in which the horizontal journal for the main drive shaft 14 is mounted. This shaft carries the main drive pulley 16 driven by a belt 18 from a motor in the lower part of the machine. The pulley 16 idles on the shaft 14 and is connected to it when desired by a one revolution clutch mechanism 19 operated by a treadle rod 20. 20

The pulley 16 is integral with a smaller pulley 22, which consequently drives whether the clutch is operative or not. The pulley 22 drives the pulley 24 and shaft 26, which, by a bevel gearing at 28, drives an eccentric 30 having a connecting rod 32, which operates the hopper mechanism. 25

The hopper 34 is mounted on a rib 36 bolted to the column 12. A shaft 38 is mounted in the rib 36 below the hopper. The shaft 38 carries a crank arm 40 and two tight pulleys 42, 44, which are belted and cross-belted, respectively, to two pulleys 46, 48 on a shaft 50 extending into the hopper 34. The pulleys 46, 48 are loose on the shaft 50 and are frictionally clutched to it by two 40 right and left coiled springs 52, each having one end fast to a collar 53 on the shaft 50, and having their other ends wound tightly around, but not fastened to, the hubs of the pulleys 46, 48.

Thus the pulleys 46, 48 drive the shaft 50 in one direction only, i. e., that in which friction tends to wind up the springs. When the rod 32 rises or falls it turns one or the other of the pulleys 46, 48 in the driving direction, and thus keeps the shaft 50 turning intermittently in the clockwise 50 direction as seen in Fig. 1. The shaft 50 carries a spider 56 which thus rotates intermittently in the hopper and keeps the tubes therein stirred up.

The shaft 38 has a second arm 58 having an arcuate elevator 60 mounted on it. The center of 55

curvature of the elevator 60 is in the axis of the shaft 38. The oscillation of the rod 32 oscillates the elevator 60 through a slot 61 in the bottom of the hopper so that at its extreme upward position 5 its beveled end 62 comes to a position 62' in line with the end of the raceway 64, and so that at its extreme lower position it forms a bottom for the slot into which tubes may fall. The elevator 60 and the raceway 64 lie flat against the side of the 10 hopper 34 and both are beveled at 60° to form a channel down which the triangular tubes may slide with one of their flat sides vertical. The member 60, at each oscillation, picks up one or two tubes and delivers them to the end of the raceway, this end being open at the top of the triangular channel.

In order to assist in the proper alignment of the tubes and to clear the raceway, a kicker member 20 66 is provided. This is a flat member extending through a slot 67 in the side of the hopper 34 just above the raceway. It is pulled out of the hopper by a spring 68 and is swung into the hopper by an arm 70 which has a slotted connection 72 with the arm 58. The member 66 is swung into 25 the hopper, or upward, in Fig. 3, as the member 60 descends. It displaces the tubes that are lying askew on top of the raceway and tends to throw them parallel to the raceway into which they will fall if there is an empty space there, or to throw 30 them off if they do not so fall.

A spring stop member or detent 74 is fastened to the upper surface of the raceway 64 near its lower extremity, and has a bent tooth 76 at its lower end extending into a slot in the top of the raceway 64. This tooth rests upon the next lowest tube in the raceway and normally holds it and all the others above it from falling into the transferring and driving mechanism. The member 74 is adjustable along the raceway to enable it to 40 handle tubes of different lengths.

The transferring mechanism is seen from the rear in Figs. 6 and 7. It is mounted in a block 78 on the front of the column 12. It comprises a cylinder 80 mounted in a cylindrical hole in the block 45 78 and having a 60° V-shaped notch 82 in its back face. The diameter of the cylinder is at least as great as the length of the longest tube used in the machine. This notch, together with the back plate 83, which forms the rear part of 50 the block 78, constitutes a triangular channel a trifle larger than a tube. The cylinder 80 has a notch 84 cooperating with a stop 86 to define a vertical position of the channel or notch 82 (Fig. 7) in which it registers with similar holes in the 55 top and bottom of the block 78 and an oblique position (Fig. 6) in line with the raceway. The cylinder is moved from one of these positions to the other by a crank arm 88, operated by a link 90 whose upper end is connected to a crank 92 on a 60 shaft 94. The shaft 94 is operated to pull the notch 82 to vertical position by a rod 96 connected at its upper end to another crank arm on the shaft 94 and at its lower end at 97 to a crank arm 98 on a shaft 100, integral with another crank 102 65 which has a resilient connection at 103 with an arm 104 loosely mounted on the shaft 100 and operated by the treadle rod 20. The clutch rod 19 is operated by the arm 104. The cylinder 80 is thrown into oblique position by a spring 106 on 70 the shaft 94.

Depression of the treadle therefore throws the notch 82 into vertical position, so that a tube 108 in the slot drops into driving position on a resilient dog 110. At the same time a lug 112 on the 75 arm 88 swings against the stop 74 and lifts it off

the tube 113, allowing it to fall against the side of the cylinder 80, where it rides, while the catch 74 drops on to the next tube 114 (Fig. 7). The lug 112 is adjustable, on the arm 88, to an inoperative position where it will not strike the detent or stop 74. This enables the operator to turn the machine over without clogging it with tubes. The detent 110 is slidable under pressure of a spring 116 on the front of the block 78. Its V notch is beveled a little at the top to permit the 10 descending tube, when driven, to crowd it forward to allow the tube to pass.

The tube is driven by a driver, in the form of a triangular plunger 118, arranged to enter the tube being driven, with a shoulder to limit such entry, 15 and with a slot 120 in its rear face to receive that part of the tube that is struck up by an indenting tool 121. This construction is the same as in the Gentile application above referred to. The driver 118 is mounted in a block 122 sliding up and down 20 in a guideway in the column 12 and is operated by a lever 124 having a pivotal link connection 126 with the column 12. Its rear end is connected by a link 128 with a crank pin 130 on the shaft 14.

The indenting tool 121 is spring-pressed back out of operative position, and is driven into the side of a tube in the cylinder 80 just before the driver begins to lower the tube by a cam 131 attached to the shaft 14 which strikes the rear end 30 132 of the indenter 121.

The heel supporting means comprises a table 134 vertically adjustable at 135 and angularly adjustable about an axis 136, and having a gage member 138 adjustable laterally and longitudinally of a heel 140 on the table, by two clamp screws 142, 144. The table 134 is resilient and pressure on the heel forces it down until the heel drops on to fixed teeth 146, as described in United States Letters Patent No. 1,895,106, granted 40 January 24, 1933, on the application of H. W. Rüss. The table 134 receives the heel 140 with its attaching face downward. The top-lift end of the heel is held by a presser member 148 pivoted at 150 on the column 12 and having an arm 152 45 which is pulled by a spring-pressed rod 154, which thus tends to hold the presser member 148 down on the heel.

The pressure member 148 is shown in detail in Fig. 5. It carries on its lower face an adjustable 50 U-shaped gage 156 with a beveled lower edge, opposite which is a second gage 158 for engaging the breast edge of the top-lift end of the heel, likewise beveled at 161 and pivoted at 160 on an adjustable block 162. Its operative edge 161 is 55 thrown downward by a leaf spring 164.

The member 148 is lifted by a link 166 attached to the lever 124 and is pressed down on the heel by the spring-pressed rod 154, as the driver 118 begins to descend.

In operating the machine the operator places a heel 140 on the table 134, as shown in Fig. 4, and steps on the treadle. The cylindric transfer member 80, which already has a tube 108 in it (Fig. 6), is turned to the Fig. 7 position and a tube 113 is 65 released to fall against the cylinder by the treadle movement as the clutch is tripped. The lever 124 rocks, and the presser member 148 descends on to the heel, the members 156, 161 camming down on the top-lift end of the heel 140. The driver descends, enters the tube 108, supports it against the thrust of the indenting tool 121, and drives it into the heel 140, and is then retracted and the machine stops. Meanwhile the member 149 rises and releases the heel 140, and the transfer mem- 70 75 75

ber 80 turns back to its Fig. 6 position allowing the tube 113 to fall into it as shown at 108 in Fig. 6, the tube 114 (Fig. 7) being held by the detent 74.

5 The relative movements of the treadle rod 20, the clutch rod 19 and the transfer operating rod 96, which are necessary to enable them to perform their functions, are such that if the transfer member is not turned sufficiently to aline its notch 82 with the driver, the clutch will not be tripped. The resilient mechanism at 103 will reach its limit of movement unless the transfer operates properly, and further descent of the arm 104 to throw the clutch is prevented.

10 Having described our invention, what we claim as new and desire to secure by Letters Patent of the United States is:

1. In a machine for driving work pieces, a raceway along which the work pieces are advanced, 20 a transfer member movable at the end of the raceway and having a passage for alinement with said raceway and a surface by which delivery from the raceway is stopped, and a retaining member for engagement with a work piece spaced in the 25 raceway from the transferring member by an amount substantially equal to the length of a work piece.

2. In a machine for driving work pieces, a raceway along which the work pieces are advanced, 30 a transfer member movable at the end of the raceway and having a passage for alinement with said raceway and a surface by which delivery therefrom is stopped, a retaining member for engagement with a work piece spaced in the race- 35 way from the transferring member, and a driver movable in the transferring member passage.

3. In a machine for driving linear work pieces, 40 a hopper, a raceway fed by the hopper and arranged to convey the linear work pieces end to end, a movable transfer member arranged, in one position, to receive a work piece from the raceway and to move it into driving position, a 45 detent arranged to act upon that work piece that is approximately the length of one work piece from the lower end of the raceway, to prevent that work piece from moving through the raceway, means for releasing said detained work piece after the work piece below it has been removed from receiving position by the transfer member, 50 whereby the heretofore detained work piece may fall into position to be received by the transfer member upon its return to receiving position, and a driver for driving a work piece out of the transfer member when in driving position.

55 4. In a machine for driving linear work pieces, an inclined raceway, a transfer member movable between receiving and driving positions and having a channel which is collinear with the raceway when the transfer member is in receiving position, 60 said transfer member being arranged to block the end of the raceway when it is not in receiving position and to support a work piece in the end of the raceway at such time, and a detent arranged to detain the work piece in the position 65 next above that of the supported work piece in the raceway at all times except for a time after the transfer member has moved from receiving position and has consequently blocked the raceway, during which time the work piece theretofore detained falls to the end of the raceway and rests on the blocking surface of the transfer member, and after which time the detent engages the 70 next work piece above the previously detained 75 work piece.

5 In a machine for driving linear work pieces, a hopper, a raceway fed by the hopper and arranged to handle the linear work pieces end to end, a movable transfer member having a work piece receiving passage arranged, in one position, to be a continuation of the raceway and to receive a work piece therefrom and in another position to hold a work piece in driving position, said transfer member being arranged when in driving position to block the end of the raceway and to 10 detain the ultimate tube therein, a detent arranged to detain the penultimate work piece in the raceway from the time that the ultimate work piece falls on the transfer member to the time that the transfer member has again blocked the 15 end of the raceway after receiving the ultimate work piece, and means for then releasing the penultimate work piece from the detent, to permit it to fall against the blocked end of the raceway, whereby the antepenultimate work piece becomes 20 the penultimate work piece and is detained as before.

6 In a machine for driving linear work pieces, a hopper, a raceway fed by the hopper and arranged to handle the linear work pieces end to 25 end, a movable transfer member arranged, in one position, to receive a work piece from the raceway and to move it into driving position, a detent arranged to act upon that work piece which is next behind that work piece in the race- 30 way that is next to be received by the transfer member on its next return to receiving position, a driver, a clutch for connecting it to a power device, and an operator-controlled member for operating the clutch and for moving the transfer 35 member from receiving to driving position, the mechanism being so arranged that the movement of the transfer member to driving position must be completed before the clutch is thrown into 40 operation, whereby damage to the driver due to striking an improperly positioned transfer member is avoided.

7. In a machine for driving linear work pieces, a hopper, a raceway fed by the hopper and arranged to handle the linear work pieces end to 45 end, a movable transfer member arranged, in one position, to receive a work piece from the raceway and to move it into driving position, a driver, a clutch for connecting it to a power device, and an operator-controlled member for operating the clutch and for moving the transfer member from receiving to driving position, the mechanism being so arranged that the movement of the transfer member to driving position must be completed before the clutch is thrown into 50 operation, whereby damage to the driver due to striking an improperly positioned transfer member is avoided.

8. In a machine for driving linear work pieces, a hopper, a raceway fed by the hopper and arranged to handle the linear work pieces end to end, a movable transfer member arranged, in one position, to receive a work piece from the raceway and to move it into driving position, a detent arranged to act upon that work piece 65 which is next behind that work piece in the raceway that is next to be received by the transfer member on its next return to receiving position, a driver, a clutch for connecting it to a power device, a manually operated member for operating 70 the clutch and for moving the transfer member from receiving to driving position, the mechanism being so arranged that the movement of the transfer member to driving position must be completed before the clutch is thrown into oper- 75

ation, and means actuated in consequence of the movement of the manually operated member for releasing the detent after the transfer member has moved from receiving position, to drop another work piece into receiving position.

9. In a machine for driving linear work pieces, a hopper, a raceway fed by the hopper and arranged to handle the linear work pieces end to end, a movable transfer member arranged, in one position, to receive a work piece from the raceway and to move it into driving position, a detent arranged to act upon that work piece which is next behind that work piece in the raceway that is next to be received by the transfer member on its next return to receiving position, a driver, a clutch for connecting it to a power device, a manually operated member for operating the clutch and for moving the transfer member from receiving to driving position, the mechanism being so arranged that the movement of the transfer member must be completed before the clutch is thrown into operation, and means operated by the transfer member in moving from receiving to driving position, to release the detent to drop another work piece into receiving position.

10. In a machine for driving work pieces, a hopper, a raceway fed by the hopper, an elevator for lifting work pieces to the end of the raceway, and a kicker member movable transversely of the raceway and arranged to move work pieces that may be delivered on to the raceway in misalignment.

11. In a machine for driving work pieces, a hopper, a raceway fed by the hopper, an elevator for lifting work pieces to the end of the raceway, and a kicker member arranged to enter the hopper above the raceway as the elevator descends,

and to move transversely of the raceway to move work pieces that may be delivered on to the raceway in misalignment.

12. In a machine for driving work pieces, a raceway, a rotatable agitator cooperating therewith, an oscillatory driving member, connecting means for communicating to the agitator movement of the driving means in one direction, and other connecting means for communicating to the agitator the movement in the opposite direction.

13. In a machine for driving work pieces, a hopper, a raceway fed by the hopper, a rotary member for agitating the work pieces in the hopper, a shaft on which said rotary member is mounted, a loose pulley on the shaft, a coil spring having one end connected to one of the two elements just mentioned and frictionally engaging the other, and means for driving the pulley in the direction in which friction will tighten the unfastened end of the spring around that element on which it is wound, to drive the agitator member.

14. In a machine for driving work pieces, a hopper, a raceway fed by the hopper, a rotary member for agitating the work pieces in the hopper, a shaft on which said rotary member is mounted, two loose pulleys mounted on the shaft, each pulley being connected to the shaft independently of the other by a coil spring wound tightly around, but not fastened to, one of the members so connected, and fastened to the other said member, and means for oscillating the pulleys simultaneously in opposite directions, whereby the shaft is driven always in the same direction.

RALPH F. KNIGHT.
